UNITED STATES PATENT OFFICE.

BENJAMIN WOLHAUPTER, OF FENTON, MICHIGAN.

CATTLE-GUARD FOR RAILWAYS.

SPECIFICATION forming part of Letters Patent No. 447,394, dated March 3, 1891.

Application filed July 30, 1889. Serial No. 319,165. (No model.)

To all whom it may concern:

Be it known that I, BENJAMIN WOLHAUPTER, a subject of the Queen of Great Britain, residing at Fenton, county of Genesee, State 5 of Michigan, have invented a certain new and useful Improvement in Cattle-Guards for Railways; and I declare the following to be a full, clear, and exact description of the same, such as will enable others skilled in the art to 10 it pertains to make and use the same, reference being had to the accompanying drawings, which form a part of this specification.

My invention relates to an improved form 15 of railway cattle-guard known as a "surface-guard," and has for its object to provide certain improvements in the construction thereof to render the device stronger and more effective.

20 In the drawings, Figure 1 is a plan, and Fig. 2 a cross-section, of my guard. Fig. 3 is a view of the supporting-piece.

In carrying out my invention, A represents the rails, and B the ties, of a railroad-track. 25 F are the longitudinal bars, of what may be termed "angle-iron," with unequal legs, the long leg f resting on the ties at an angle of about forty-five degrees, thus throwing the point of the angle f' upward and the short 30 leg f'' downward a short distance. These longitudinal bars F are held in place at each end by a bolt G, which passes through each one and is secured by the nuts g on the ends and by the intermediate pieces H. These pieces 35 have their edges shaped to conform to the shape of the pieces F, and they are provided with projections h, which, entering the slots f''' of the bars F, serve to keep the intermediate pieces in an upright position, and thus the 40 whole structure is held firmly together.

In order to prevent anything which may be dragging on a passing train from catching on the guard, I prefer to bevel the corners f⁴ of

the longitudinal bars F. Of course, if desired, two or three of the ties may be extended 45 out on both sides of the track and a grating similar to the one between the tracks be located there. If desired, the longitudinal bars may be made of unequal height, as shown in Fig. 2; but I do not care to limit myself to 50 this.

It will be observed that the inclined bars extend parallel with the track-rails. This is superior to a construction wherein the bars extend across from rail to rail, for several 55 reasons. The edge of the bars which extends upward acts to split the animal's hoof when it attempts to cross on top of the bars, and when its foot slides between the bars the sharp horizontal edge of the adjacent bars 60 presses into the side of its ankle. So, also, when the bars extend longitudinally between the track-rails, anything which may be dragging on a passing train will slide freely over the bars and will not be caught, as might be 65 the case when the bars extend at right angles to the track-rails.

What I claim is—

1. A railway cattle-guard consisting of the longitudinal bars F, the longer legs f of which 70 rest on the ties and the shorter legs f² are bent over to form the angles f', and the bolts G, passing through said bars to clamp them together, substantially as described.

2. A railway cattle-guard consisting of the 75 longitudinal bars F, of angle-iron shape, the bolts G, and the intermediate pieces H, of a shape to conform to the bars F, substantially as described.

In testimony whereof I sign this specifica- 80 tion in the presence of two witnesses.

BENJAMIN WOLHAUPTER.
